(57) **CLAIM**

The ornamental design for a virtual reality headset, as shown and described.

DESCRIPTION

FIG. 1 is a front, left, and top perspective view of a virtual reality headset, showing my design.

FIG. 2 is a rear, right, and bottom perspective view thereof.

FIG. 3 is a rear elevation view thereof.

FIG. 4 is a front elevation view thereof.

FIG. 5 is a right side elevation view thereof.

FIG. 6 is a left side elevation view thereof.

FIG. 7 is a top plan view thereof; and,

FIG. 8 is a bottom plan view thereof.

The broken lines shown in the drawings are included for the purpose of illustrating portions of the virtual reality headset that form no part of the claimed design.
